Specification for Design.

Patented May 4, 1915.

Application filed November 19, 1914. Serial No. 873,056. Term of patent 14 years.

To all whom it may concern:

Be it known that I, GEORGE BUERMANN, a citizen of the United States, residing at Newark, county of Essex, and State of New Jersey, have invented a new, original, and ornamental Design for Cinch-Rings, of which the following is a specification, reference being had to the accompanying drawing, forming part thereof.

Figure 1 is a face view of a cinch ring showing my new design. Fig. 2 is a central

cross-section of a ring illustrated in Fig. 1 and showing clearly the curvature of one side of the ring and proportionate curvatures of the inner and outer edges.

I claim:

The ornamental design for a cinch ring, as shown.

GEORGE BUERMANN.
